UNITED STATES PATENT OFFICE.

WILLIAM J. KERR, OF SMETHPORT, PENNSYLVANIA.

TOP.

1,338,572.

Specification of Letters Patent. Patented Apr. 27, 1920.

Application filed July 14, 1919. Serial No. 310,523.

To all whom it may concern:

Be it known that I, WILLIAM J. KERR, a citizen of the United States, residing at Smethport, in the county of McKean and State of Pennsylvania, have invented certain new and useful Improvements in Tops; and I do declare the following to be a full, clear, and exact description of the invention, such as will enable others skilled in the art to which it appertains to make and use the same.

My invention relates to amusement devices and more particularly to a spinning top, one object of the invention being to provide a device of this class which may be easily and inexpensively manufactured and marketed, yet one which will produce a great deal of amusement, while another object is to provide for rotating the casing of the top by the action of a main rotary disk and one or more smaller disks in said casing.

A still further object is to permanently attach a spinning cord to the device so that when it is unwound to set the top in motion it will be immediately rewound for further use.

With the foregoing in view, the invention resides in the novel construction and arrangement of parts hereinafter described and claimed, reference being made to the accompanying drawing which forms a part of this application.

Figure 1 is a vertical section of a top constructed in accordance with my invention, showing parts in elevation.

Fig. 2 is a top plan view.

Fig. 3 is a horizontal section on the plane indicated by line 3—3 of Fig. 1.

Fig. 4 is a top plan view showing a different form of construction.

Fig. 5 is a vertical section on the plane of line 5—5 of Fig. 4.

In the form of the invention shown in Figs. 1, 2 and 3, the numeral 1 designates a shallow cup-like casing preferably formed of sheet metal and having a solid bottom 2, an open top 3, and a circular vertical wall 4. At its center, the bottom 2 is stamped downwardly to simultaneously provide a bearing socket 5 at the upper side of said bottom and a bearing center 6 at the lower side thereof, the latter being adapted to rest on any horizontal surface to revolutionally support the device. An arched staff retainer 7 has its crown spaced above the

socket 5 and provided with a circular opening, 8, while the legs of said retainer are secured to the bottom 2 in any suitable manner, as by forming them with tongues 9 which are passed through slots and clenched.

A frame member spans the open top 3 of the casing 1 and preferably consists of an arched spider 10 whose legs 11 are suitably secured at 12 to the wall 4 of said casing, preferably by passing said ends through slots and clenching them as shown in Fig. 1. A spider 13 is disposed slightly below the crown of the frame member 10 and its legs are appropriately secured at 14 to the legs 11, while the center of said spider is formed with an opening 15 vertically aligned with the socket 5. A vertical staff 16 is received rotatably in the openings 8 and 15 and is provided with bearing centers 17 at its ends, one of these centers resting in the socket 5 while the other bears against the crown of the frame member 10. The retainer 7 and the spider 13 serve to prevent tilting of the staff and to prevent possible slippage thereof from the socket 5.

The staff 16 fixedly carries a horizontal disk 18 located within the casing 1 with its peripheral edge in close relation with the circular wall 4, and said disk and staff are adapted to be rotated by means of a cord 19 wound on the staff 16 and having one end attached to said staff in such manner as to remain connected therewith when the cord is totally unwound to set the device in motion. By this arrangement, the cord is immediately rewound for further use, and considerable amusement is afforded by endeavoring to cause said cord to rewind in orderly fashion. A half spool 20 is preferably secured on the staff 16 near its upper end and one end of the cord 19 may be passed through a groove 21 in said half spool and knotted at 22. The spool serves to prevent entanglement of the cord in the upper part of the device and may also be used to turn the staff 16 when winding the cord by hand.

Supported on the disk 18 and preferably loose therefrom, are a suitable number of small disk 23 which are provided with depending bearing centers or studs 24 which are preferably pointed as shown to rest on the disk 18 with as little friction as possible. The disks 23 are adapted to travel around the wall 4 when the disk 18 is set in motion and they thus serve to cause the entire cas-

ing 1 and the parts secured thereto, to revolve upon the bearing center 6, thereby producing a very pleasing effect, particularly if the several moving parts are ornamented by painting, fancy printing, etc., and it is to be understood that this ornamentation may be carried out in any desired way. Also, the disks 23, although shown circular, may well be of any desired form, 10 such as elliptical, star-shaped, etc.

In the form of construction shown in Figs. 4 and 5, the casing 1^a is preferably formed of a block of wood provided with a socket whose wall 4^a is of circular form. 15 The bottom 2^a of the casing 1^a is provided with a central bearing socket 5^a and an arched retainer 7^a extending over said socket and provided with a central opening 8^a. A frame member 10^a spans the open top of the 20 casing and is preferably in the form of a straight strip of metal having its ends attached to the casing by tacks or screws 12^a. At its center the bar 10^a is formed with an opening 15^a, and a vertical staff 16^a passes 25 through this opening and is provided at its lower end with a bearing center 17^a engaging the socket 5^a. Above the bar 10^a the staff is shown provided with a half spool 20^a and spinning cord 19^a, while below said 30 bar a block of wood 25 is secured on said staff to carry a horizontal disk 18^a which may be secured thereto by tacks or the like. 26. I support a suitable number of small disks 23^a on the disk 18^a and I have shown 35 them provided with depending bearing centers 24^a loosely received in openings 27 in the disk 18^a.

The form of the device last described is operated in the same manner as the type 40 shown in Figs. 1, 2 and 3 and if the casing 1^a be provided with a depending bearing center, it could be made to rotate, but this is a more simple and less expensive form of device and it preferably includes only the 45 features shown, but it is to be understood that these features may be varied in numerous ways as to size, shape, ornamentation, etc.

From the foregoing, taken in connection 50 with the accompanying drawing, it will be seen that although both forms of my invention are of simple and inexpensive nature, they will be highly amusing, and since probably the best results may be obtained from 55 the details disclosed, they may well be followed. I wish it understood however that within the scope of the invention as claimed, numerous minor changes may well be made.

I claim:

60 1. A top comprising a casing having a circular vertical wall, an open top and a central bearing socket in the upper side of its bottom, a frame member spanning the open top of said casing and having a bearing 65 alined with said bearing socket, a verti-

cal staff rotatably engaged with said bearing and socket, an arched retainer having an opening in its crown receiving said staff, the legs of said retainer being secured to the bottom of the casing, a disk carried fixedly 70 by said staff within said casing and having its periphery in close relation with said circular wall, and a cord for spinning said staff and disk.

2. A top comprising a casing having a circular vertical wall, an open top and a central bearing socket in the upper side of its bottom, a frame member spanning the open top of said casing and having a bearing alined with said bearing socket, a vertical staff 80 rotatably engaged with said bearing and socket, an arched retainer having an opening in its crown receiving said staff, the legs of said retainer being secured to the bottom of the casing, a disk carried fixedly by said staff within said casing and having its periphery in close relation with said circular wall, a cord for spinning said staff and disk, and a small disk rotatably supported by said first named disk, the peripheral edge 90 of said small disk being adapted to contact with said circular wall while the device is in motion.

3. A top comprising a casing having a circular vertical wall, a horizontal spinning 95 disk rotatably mounted in said casing and having its edge in close relation with said wall, and a small disk supported by said spinning disk for running contact with said wall, said last mentioned disk having a de- 100 pending central bearing stud.

4. A top comprising a casing having a circular vertical wall, a horizontal spinning disk rotatably mounted in said casing and having its edge in close relation with said wall, and a small disk supported by said spinning disk for running contact with said wall, said disk having a depending central bearing stud sharpened and resting on said 105 spinning disk.

5. A top comprising a casing having a circular vertical wall and a bottom, said bottom having at its upper side a central bearing and at its lower side a central bearing center, the latter being adapted to rest 115 on a support to revolvably support the casing, a vertical staff in said casing supported by said bearing, means for holding said staff against tilting, a horizontal disk fixedly carried by said staff and located in said casing to be spun by rotation of said staff, and a small disk supported by said horizontal disk, the peripheral edge of said small disk being adapted to travel on said circular wall to rotate said casing on said center when the 125 device is set in motion.

6. A structure as specified in claim 5; said bearing and said center being formed by stamping the central part of the casing bottom downwardly.

7. A top comprising a casing having an open top and provided with a bearing at the center of its bottom, an arched spider-like frame extending over the casing and having its legs secured to said casing, a spider below the crown of said frame and having a central opening, the ends of said spider being secured to the legs of said frame, a vertical staff having bearing centers at its ends, the 10 lower center resting on said bearing and the

upper center contacting with the crown of said frame, said staff passing through the opening of said spider to prevent tilting of said staff, and a spinning member fixedly carried by said staff and located in said 15 casing.

In testimony whereof I have hereunto set my hand.

WILLIAM J. KERR.
